UNITED STATES PATENT OFFICE.

HENRY M. QUACKENBUSH, OF HERKIMER, NEW YORK.

DESIGN FOR A TACK OR NAIL EXTRACTOR.

SPECIFICATION forming part of Design No. 33,080, dated August 14, 1900.

Application filed May 4, 1900. Serial No. 15,550. Term of patent 7 years.

To all whom it may concern:

Be it known that I, HENRY M. QUACKENBUSH, a citizen of the United States, residing at Herkimer, in the county of Herkimer and State of New York, have invented and produced a new and original Design for a Tack or Nail Extractor, of which the following is a specification.

My present invention pertains to a new and original design for tack or nail extractors, the same being illustrated in the annexed drawings, wherein—

Figure 1 is a perspective view of the device; Fig. 2, a front face view, and Fig. 3 a rear face view.

The leading and essential features of my

design consist of the main body portion A, the loop B at the upper end thereof, the downturned end C, extending from the loop, and the claw D, formed upon the opposite ²⁰ end of the main body.

Having thus described my invention, what I claim is—

The design for a tack or nail extractor substantially as shown and described. ²⁵

In witness whereof I hereunto set my hand in the presence of two witnesses.

HENRY M. QUACKENBUSH.
